CLAIM

The ornamental design for telephone set with a digital clock, as shown.

DESCRIPTION

FIG. 1 is a front top perspective view of a telephone set with a digital clock showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof; and

FIG. 8 is a rear perspective view when a hand set removed from the base.
